UNITED STATES PATENT OFFICE

113,222

DESIGN FOR A PENDANT OR SIMILAR ARTICLE

Adolf Fehr, Attleboro, Mass.

Application December 22, 1938, Serial No. 81,943

Term of patent 3½ years

To all whom it may concern:

Be it known that I, Adolf Fehr, a citizen of the United States of America, residing at Attleboro, county of Bristol, and State of Massachusetts, have invented a new, original, and ornamental Design for a Pendant or Similar Article, of which the following is a specification, reference being had to the accompanying drawing, forming a part thereof.

Fig. 1 is a front elevational view of a pendant showing my new design; and

Figs. 2 and 3 are sectional views taken on lines 2—2, 3—3, respectively, of Fig. 1.

I claim:

The ornamental design for a pendant or similar article, substantially as shown.

ADOLF FEHR.
